UNITED STATES PATENT OFFICE.

GEORGE F. SEITZ, OF PHILADELPHIA, PENNSYLVANIA.

SUPERHEATER ATTACHMENT FOR FURNACES.

Application filed November 21, 1921. Serial No. 516,826.

To all whom it may concern:

Be it known that I, GEORGE F. SEITZ, a citizen of the United States, residing at Philadelphia, in the county of Philadelphia and State of Pennsylvania, have invented new and useful Improvements in Superheater Attachments for Furnaces, of which the following is a specification.

This invention relates to stoves and furnaces, and has for its object the provision of a device adapted to be located within the fire box and partly embedded within the coals therein, the device being for the purpose of promoting combustion of the gases rising from the coal whereby to utilize every bit of combustible matter and produce a much hotter fire than is ordinarily obtained.

An important object is the provision of an attachment of this character which includes means for forming superheated steam, mixing it with air and then blowing the mixture into the bed of coals, the mixture combining with the gases arising from the coal during burning thereof and producing a highly combustible gaseous mixture which will burn violently and produce a very hot sheet of flame.

Another object is the provision of a device of this character which comprises means for forming superheated steam and blowing it forcibly through the bed of coals, the steam being used either alone or in conjunction with air.

An additional object is the provision of a device of this character which will be comparatively simple and inexpensive in manufacture and installation, highly efficient in use, durable in service, positive in action, and a general improvement in the art.

With the above and other objects and advantages in view, the invention consists in the details of construction to be hereinafter more fully described and claimed and illustrated in the accompanying drawings in which—

Figure 1 is a view of a portion of a furnace, parts being broken away to show my device in position.

Figure 2 is a detail sectional view through a portion of the furnace showing my superheater mounted therein.

Figure 3 is a longitudinal section taken through the humidifier.

Figure 4 is a detail end elevation thereof.

Figure 5 is a longitudinal section through the superheater.

Figure 6 is a section taken at right angles to Figure 5.

Referring more particularly to the drawings, the letter A designates a portion of a furnace and B designates the fire box thereof. In carrying out my invention I provide a superheater 10 which is located within the fire box and which is partially embedded within the mass of coals within the furnace or stove. Leading from the upper portion of this superheater is a pipe 11 which extends through one side of the furnace and which may be suitably secured thereto by any desired means. This pipe leads to a humidifier or water admixing device indicated broadly by the numeral 12. The superheater might be secured in position in any one of various ways, though I have shown it as provided with lugs 13 which engage against the top of the fire box lining. I also provide other lugs 14 which extend from the rear side of the superheater near the lower portion thereof and which engage against the lining for holding the superheater proper in spaced relation to the lining.

The superheater is here illustrated as being of rectangular formation, though it is conceivable that some other shape might be used and it is to be understood that it may be constructed of any suitable or preferred material capable of withstanding the heat generated within a furnace. This superheater casing is formed internally with a plurality of channels 15 arranged as clearly disclosed in Figure 5, one channel having the pipe 11 leading thereto. The outermost channels are enlarged to define expansion pockets 16 and the wall of the superheater farthest from the lining of the fire box is provided with a series of countersunk holes or perforations 17 of suitable diameter, which communicate with one endmost channel 15 and the pocket therein.

The humidifier portion of the device, indicated broadly by the numeral 12, comprises an elongated casing 18 which is lined throughout the major portion of its length with absorbent material 19. The pipe 11 leads from one end of this casing 18 and the other end is formed with an air vent and overflow hole 20 which is capable of be-

ing covered or uncovered to a variable extent by means of a pivoted cover 21. This second mentioned end of the casing is formed with an upward extension 22 which is of sufficient size to admit and hold the neck of a bottle 23. Held within the neck of the bottle is a suitable stopper 24 through which extends a wick 25 which serves to permit water within the bottle to drip into the casing 18 so that the latter will always be supplied with moisture as long as there is any water in the bottle.

The operation of the device is as follows:—

- 15 When there is a fire in the furnace and it is desired to put my device into operation, it is necessary to pour water into the casing 18 until it overflows through the vent hole 20. The bottle equipped with the stopper and wick is then inverted and engaged within the upward extension 22 so as to allow water to drip continually into the casing 18 for maintaining the water therein at a constant level. Air will be drawn into the casing 18 through the hole 20 and in passing over the water will produce a moist mixture which will pass through the pipe 11 into the superheater. The bore of this pipe should be sufficiently large to counterbalance the pressure which exists in the superheater. As the superheater is partially embedded within the burning coals, it will be apparent that the moisture in the air passing thereto, will be converted into steam which will moreover become superheated during its passage through the serpentine channels 15. The steam and air are of course greatly expanded under the influence of the heat and the mixture will be forcibly ejected through the perforations 17, the superheated steam and air thus being forced through the burning coals and supplying thereto the requisite oxygen to insure perfect combustion so that the coal or other fuel will be entirely consumed with the production of an almost negligible quantity of ash. This mixture coming in contact and intimately commingling with the gases generated within the furnace, produces an extremely highly combustible gaseous mixture which burns violently and which not only gives off intense heat but which also insures the consumption of all the fuel so that there is practically no waste in the form of ashes. 55 Another advantage is that there will be hardly any smoke as the carbon, soot, and the other elements which go to make up smoke, are all consumed and converted into useful energy.
- 60 If a stronger fire is desired, the stopper in the neck of the bottle is loosened to permit the water to drip more freely into the casing 18, and the air vent 20 is closed by swinging the cover 21 over it. This will of course result in the formation of a larger

70 quantity of superheated steam which will cause a much stronger flow into and among the coals, this superheated steam generating more gas and causing a greater or hotter fire.

75 If a slow burning fire is desired, a comparatively small quantity of water should be poured into the casing 18 and the bottle be removed entirely so that more air in proportion to the superheated steam will pass into the fire.

80 It will be observed that I have shown and described the bottle having the stopper and wick as a water supply means, but it should be distinctly understood that any other means might be employed for causing water to drip into the humidifier casing, absolutely no limitation being desired in this respect. This particular arrangement is, however, 85 convenient and inexpensive and will operate efficiently.

90 While I have shown and described the preferred embodiment of my invention, it is of course to be understood that I reserve the right to make such changes in the form, construction and arrangement of parts as will not depart from the spirit of the invention or the scope of the subjoined claims.

95 What is claimed is:—

1. A furnace attachment comprising a superheater located within the fire box of a furnace and formed with a serpentine passage and a plurality of perforations communicating with the passage, a pipe leading into said passage and leading through one side of the furnace, and means for supplying water and air alone or together through said pipe into the superheater.

100 2. A furnace attachment comprising a superheater located within the fire box of a furnace, said superheater being formed with a serpentine passage expanded at intervals into pockets, the wall of the superheater most remote from the wall of the fire box being provided with a plurality of perforations communicating with one endmost branch of the passage, and a water and air inlet pipe leading from the outside of the furnace into the other endmost branch of the passage.

110 3. A furnace attachment comprising a superheater located within the fire box of a furnace and formed at its upper end with lugs seating upon the top of the fire box lining and formed upon its rear wall near its lower end with a plurality of other lugs engaging against the adjacent wall of the lining, said superheater being formed with passages and outlet perforations, and a conducting pipe leading into the superheater.

115 4. A furnace attachment comprising a superheater located within the fire box of a furnace and having passages and outlet perforations, a conducting pipe leading into the passages and extending to the outside of

the furnace, a casing connected with the outer end of said pipe and having a lining of absorbent material, said casing having one end formed with an upturned extension 5 and a controllable air inlet opening, and means for supplying water into said casing and through said upturned end.

5. A furnace attachment comprising a superheater located within the fire box of a 10 furnace and provided with perforations, a casing located exteriorly of the furnace and

having one end carrying a pipe connected with and communicating with the superheater, the other end of said casing being upturned, means for supplying water into 15 said upturned end, said upturned end portion being formed with an opening, and a movably mounted shutter on said upturned end for partly or entirely closing said opening.

In testimony whereof I affix my signature.

GEORGE F. SEITZ.
